UNITED STATES PATENT OFFICE.

FRANK EHRHARDT, OF NEWARK, NEW JERSEY.

REFUSE-DEPOSITORY.

1,109,911.

Specification of Letters Patent.

Patented Sept. 8, 1914.

Application filed October 14, 1913. Serial No. 795,042.

To all whom it may concern:

Be it known that I, FRANK EHRHARDT, a citizen of the United States, residing at Newark, in the county of Essex and State of New Jersey, have invented certain new and useful Improvements in Refuse-Depositories; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

The present invention relates, generally, to improvements in refuse depositaries; and, the invention has reference, more particularly, to a concealed depository for ashes or refuse from which collections may be conveniently made by the community refuse collectors, but which is in such form as to have a fixed location adjacent to the curb of the foot-walk, and constructed to be non-removable from such fixed location, yet provided with mechanism whereby the depository proper may be elevated and easily emptied into the refuse collector's wagon.

A further object of the present invention is to provide a fixed refuse depository together with simple and easily operated mechanism for raising and dumping the same, which when in normal condition or arrangement provides the appearance and uses of a stepping-stone or carriage-block and tie or hitching-post; the same being so arranged that when normally arranged the depository proper remains concealed, and the contents covered and protected against exposure to wind, sun, storm, or other elemental disturbance.

Other objects of the present invention, not at this time more particularly enumerated, will be clearly understood from the following detailed description of the present invention.

With the objects of the present invention in view the same consists, primarily, in the novel refuse depository hereinafter set forth; and, furthermore, the said invention consists in the novel arrangements and combinations of the several devices and parts, as well as in the details of the construction of the same, all of which will be hereinafter more fully described in the following specification, and then finally embodied in the clauses of the claims which are appended to

and which form an essential part of the said specification.

The invention is clearly illustrated in the accompanying drawings, in which:

Figure 1 is a plan view of the novel refuse depository in its normal closed position; and Fig. 2 is a front elevation of the same. Fig. 3 is a vertical longitudinal section of the same taken on line 3--3 in said Fig. 1; Fig. 4 is a vertical cross section of the same taken on line 4--4 in said Fig. 3.

Similar characters of reference are employed in all of the above described views to indicate corresponding parts.

Referring now to the said drawings the reference character 1 indicates the pavement of the roadway, 2 indicates the curb, and 3 the side or foot-walk of the street.

The reference character 4 indicates a main casing which is partially sunk into the earth at or adjacent to the curb 2, so that its upper part projects above the surface of the side or front-walk 3. Located within said main casing 4 is a partition member 5 of any desirable conformation. Secured to said partition-member 5, so as to extend downwardly therefrom and through the bottom of said main casing 4, are tubular guide-members 6, in which are slidably mounted, so as to be vertically movable therein, rack-members 7. Said partition-member 5 is provided with suitable openings 8, registered above the upper ends of said guide-members 6, through which said rack-members 7 may extend, or be projected. Said guide-members 6, and their rack-members 7, normally extend down into the earth beneath said main casing, and in order to prevent the earth from crowding around the same, and forcing the same out of proper alignment, and to prevent the earth from so binding the same in their sunken position as to render the same difficult of removal for purposes or repair or replacement, there are provided tubular casings 9 which extend downwardly into the earth from the bottom of said main casing 4, so as to surround said guide-members 6, and protect the same from direct contact with the earth. At the same time said tubular casings 9 tend to protect said guide-members 6 from the corroding effects of moisture and the like while in their sunken position. The upper ends of said rack-members 7, where they project through and above the openings 8 of said partition-member 5, are connected together by means

of a strap or brace 10, and also connected with said upper ends of said rack-members 7 are outwardly extending arms 11 which are turned upwardly at their free ends to provide vertical bracket-members 12. Pivotally mounted between the upper ends of said bracket-members 12, so as to swing therebetween, is a refuse-receptacle 13, the same being mounted on the journal-studs 14 secured in the free ends of said bracket-members 12. Connected with the upper marginal edge of the mouth of said refuse-receptacle 13 is an outwardly extending flange 15, which, when said refuse-receptacle is in its normal lowered position, nesting within the upper portion of said main-casing 4, engages and rests upon the marginal edge of the mouth of said main casing. Pivotally connected with the outer longitudinal edge of said refuse-receptacle 13, by means of any suitable hinge-connection 16, is a cover-member 17, which when closed extends over the mouth of said receptacle, and serves not only to protect the contents of said receptacle from the atmosphere, but also as the platform of the stepping-stone or carriage-block which said receptacle provides when lowered into nesting relation with said main casing 4. Connected with the inner side of said cover-member 17, and extending laterally across the same, adjacent to each end thereof, are vertical flanges 18 which when the cover-member is closed, extend into the mouth of said receptacle 13. The purpose which the said vertical flanges serve will be mentioned more particularly hereafter. Located adjacent to one end of said main casing 4, and having its lower end sunk into the ground along side of said main casing is a hollow post-member 19. Journaled in the end walls of said main casing 4, so as to extend beneath said partition member 5 is a shaft 20. Fixed upon said shaft 20 are spur-gears 21 which, extending through openings 22 provided in said guide-members 6, mesh operatively with the teeth of said rack-members 7. One end of said shaft 20 extends into and through the lower end of said post-member 19, and secured upon that portion of said shaft 20, located within the interior of said post-member 19, is a sprocket wheel 23. Journaled in the upper end of said post-member 19, so as to extend transversely through the interior thereof, parallel to said shaft 20, is a driving-shaft 24. Fixed upon said driving-shaft 24 is a sprocket-wheel 25. Running over said sprocket-wheel 25 and said sprocket-wheel 23 is a driving chain 26, of any desirable form, or construction. Said driving-shaft 24 extends outwardly through the wall of said post-member 19, and is provided at such exteriorly presented end with a squared-end 27, adapted to receive the socketed hub 28 of a removable crank or handle-member 29,

which when so attached to said driving-shaft serves to transmit a rotary movement thereto. Also fixed upon said driving-shaft 24 is a brake-wheel or disk 30. Anchored upon a stud 31, extending inwardly from one side wall of said post-member 19, is one end of a brake-band 32 which encircles or embraces said brake-wheel or disk 30. The other end of said brake-band 32 is secured to a hand-lever 33, which is pivotally mounted or fulcrumed upon said stud 31, and which projects outwardly through a suitable opening 34 provided in the front wall of said post-member 19, so as to exteriorly present the hand-grip portion 35 of said hand-lever 33. One marginal edge of said opening 34 is provided with a plurality of notches or ratchet-like stop-portions 36 with which said hand-lever 33 may be selectively engaged to hold said brake-band 32 in braking or binding engagement with said brake-wheel or disk 30, all for purposes to be subsequently set forth. The upper exterior end of said post-member 19 may be provided with any desirable form of ornamental or fanciful head or top 37, to which may be secured a ring 38, or other suitable device, to provide means to tie to, when said post-member 19 serves as a tie or hitching-post.

The use and operation of the device is now to be explained. Normally the refuse-receptacle 13 is maintained in its lowered position, and nested within said main casing 4. Ashes, refuse, dirt, etc., may be carried thereto, and by raising the cover-member 17, deposited therein. The cover-member 17 is then closed, thereby protecting the contents of said refuse-receptacle from the sun, rain, etc., and preventing the same from being blown about by wind, while awaiting the coming of the refuse collector. When the refuse collector arrives with his wagon to collect the refuse, and desires to empty said refuse-receptacle, he drives up with his wagon along the curb, and being possessed of a detachable or portable crank or handle-member 29, he connects the same upon the driving-shaft 24. The driving-shaft 24 is thereupon rotated, thereby rotating said shaft 20, through the transmission mechanism provided by the sprocket-wheels 25 and 23 and the driving-chain 26. Said shaft 20 thereupon rotates said spur-gears 21, which meshing with the teeth of said rack-member 7, imparts to the latter an upward movement. The upward movement of said rack-members 7 elevates said refuse-receptacle 13, thereby removing the same from its nested relation with said main casing 4, and lifting the same above the level of the body of the refuse collector's wagon. Said refuse-receptacle is provided with a spring-latch member 39, having a depressed portion 40 which engages one of said bracket-members 12 to maintain said refuse-receptacle 13, normally,

against swinging on its pivotal connection with said bracket-members 12 during its elevation. Of course, it will be understood that said spring-latch member 39 may be made in various forms, or a manually operated lock means may be substituted therefor, hence, I do not limit myself to the exact form shown in the drawings. When said refuse-receptacle 13 has been raised to the desired elevation it is maintained or held in such position by drawing the brake-band 32 in braking or binding relation to the brake-wheel or disk 30 by operating the same with said hand-lever 33. When thus secured in elevated position, the refuse-receptacle is ready to be dumped or emptied. The refuse collector thereupon opens said cover-member 17, and swings or over-turns the refuse-receptacle on its pivots. The free edge of said cover-member would then rest on the side of the wagon, and the contents of the refuse-receptacle would flow over said cover and be precipitated into the said wagon. In this manner, it will be evident, the said cover-member 17 is made to serve the purposes of a chute, and consequently the vertical side flange 18, upon the inner side of said cover-member now serve as the sides of said chute, and thereby properly guide the outward flow of said refuse from the receptacle 13, and prevents any of the refuse from falling into the street or on the curb. When the receptacle 13 is thus dumped or emptied, it is turned back upon its pivotal connections, to its normal position, and then by releasing the grip of said brake-band 32 upon said brake-wheel or disk 30, the said receptacle and its rack-members 7 will fall, by gravity, easily and quickly to their normal lowered position, with said receptacle 13 again nested within said main casing 4.

Of course, it will be apparent from an inspection of the drawings, that my novel refuse depository, and its operating mechanism, inclosed as they are in the main casing 4 and post-member 19, provide the additional usefulness of a carriage-block and hitching-post, which may be given any desired ornamental adornment.

It will also be clear that the present invention provides a very useful depository for refuse, which, except during the emptying operations, is concealed itself and conceals its contents. Furthermore it cannot be thrown about as the ordinary portable refuse cans, and the like, may be, nor can it be over-turned so as to scatter, in an unsightly and unsanitary manner, its contents about, since the removable handle or crank alone can operate the same.

I am aware that some changes may be made in the arrangements and combinations of the various parts and devices of my novel refuse depository without departing from the scope of my present invention as set

forth in the foregoing description, and as defined in the clauses of the claims, which are appended to the said specification. Hence I do not limit my present invention to the exact arrangements and combinations of the various devices and parts as described in the foregoing specification, nor do I confine myself to the exact details of the construction of the said parts as illustrated in the accompanying drawings.

I claim:

1. In elevating means for refuse receptacles a main-casing adapted to be sunk in the ground, tubular guide-members extending downwardly from the bottom of said main-casing, rack-members slidably mounted in said guide-members, means for pivotally supporting a refuse-receptacle in connection with the upper ends of said rack-members, a transverse shaft journaled in the lower portion of said main-casing beneath said refuse-receptacle, spur-gears fixed upon said shaft, said guide-members being provided with openings through which said spur-gears project to mesh with said rack-members, power transmission mechanism for operating said shaft, spur-gears and rack-members and a hollow post-member adjacent to said main casing in which said power transmission mechanism is concealed.

2. In elevating means for refuse receptacles a main-casing adapted to be sunk in the ground, tubular guide-members extending downwardly from the bottom of said main-casing, rack-members slidably mounted in said guide-members, means for pivotally supporting a refuse-receptacle in connection with the upper ends of said rack-members, a transverse shaft journaled in the lower portion of said main-casing beneath said refuse-receptacle, spur-gears fixed upon said shaft, said guide-members being provided with openings through which said spur-gears project to mesh with said rack-members, power transmission mechanism for operating said shaft, spur-gears and rack-members and a detachable hand-crank for applying power to said transmission mechanism.

3. In an elevating means for refuse-receptacles a main-casing adapted to be sunk in the ground, tubular guide-members extending downwardly from the bottom of said main-casing, rack-members slidably mounted in said guide-members, means for pivotally supporting a refuse-receptacle in connection with the upper ends of said rack-members, a transverse shaft journaled in the lower portion of said main-casing beneath said refuse-receptacle, spur-gears fixed upon said shaft, said guide-members being provided with openings through which said spur-gears project to mesh with said rack-members, power transmission mechanism for operating said shaft, spur-gears and rack-

members, a detachable hand-crank for applying power to said transmission mechanism, a brake mechanism for locking said power transmission mechanism to hold said refuse-receptacle in lifted position while being dumped.

4. In an elevating means for refuse-receptacles, a main-casing adapted to be sunk in the ground, tubular guide-members extending downwardly from the bottom of said main-casing, rack-members slidably mounted in said guide-members, means for pivotally supporting a refuse-receptacle in connection with the upper ends of said rack-members, a transverse shaft journaled in the lower portion of said main-casing beneath said refuse-receptacle, spur-gears fixed upon said shaft, said guide-members being provided with openings through which said spur-gears project to mesh with said rack-members, power transmission mechanism for operating said shaft, spur-gears and rack-members, a detachable hand-crank for applying power to said transmission mechanism, a brake mechanism for locking said power transmission mechanism to hold said refuse-receptacle in lifted position while being dumped, and a hollow post-member adjacent to said main casing in which said power-transmission mechanism is concealed.

5. In an elevating means for refuse-receptacles a main-casing adapted to be sunk in the ground, tubular guide-members extending downwardly from the bottom of said main-casing, rack-member slidably mounted in said guide-members, means for pivotally supporting a refuse-receptacle in connection with the upper ends of said rack-members, a transverse shaft journaled in the lower portion of said main-casing beneath said refuse-receptacle, spur-gears fixed upon said shaft, said guide-members being provided with openings through which said spur-gears project to mesh with said rack-members, a hollow post-member mounted in the ground adjacent to said main-casing, one end of said shaft extending through the lower end of said post-member, a driving-shaft journaled in the upper end of said post-member, sprocket-wheels attached respectively upon said transverse shaft and said driving shaft, a driving-chain running over said sprocket-wheels, and a detachable hand-crank adapted to be connected with one end of said driving-shaft to apply power thereto.

6. In an elevating means for refuse-receptacles a main-casing adapted to be sunk in the ground, tubular guide-members extending downwardly from the bottom of said main-casing, rack-members slidably mounted in said guide-members, means for pivotally supporting a refuse-receptacle in connection with the upper ends of said rack-members, a transverse shaft journaled in the lower portion of said main-casing beneath said refuse-receptacle, spur-gears fixed upon said shaft, said guide-members being provided with openings through which said spur-gears project to mesh with said rack-members, a hollow post-member mounted in the ground adjacent to said main-casing, one end of said shaft extending through the lower end of said post-member, a driving-shaft journaled in the upper end of said post-member, sprocket-wheels attached respectively upon said transverse shaft and said driving shaft, a driving-chain running over said sprocket-wheels, a detachable hand-crank adapted to be connected with one end of said driving-shaft to apply power thereto, a brake mechanism for locking said power transmission mechanism to hold said refuse-receptacle in elevated position while being dumped.

end of said shaft extending through the lower end of said post-member, a driving-shaft journaled in the upper end of said post-member, sprocket-wheels attached respectively upon said transverse shaft and said driving shaft, a driving-chain running over said sprocket-wheels, and a detachable hand-crank adapted to be connected with one end of said driving-shaft to apply power thereto.

6. In an elevating means for refuse-receptacles a main-casing adapted to be sunk in the ground, tubular guide-members extending downwardly from the bottom of said main-casing, rack-members slidably mounted in said guide-members, means for pivotally supporting a refuse-receptacle in connection with the upper ends of said rack-members, a transverse shaft journaled in the lower portion of said main-casing beneath said refuse-receptacle, spur-gears fixed upon said shaft, said guide-members being provided with openings through which said spur-gears project to mesh with said rack-members, a hollow post-member mounted in the ground adjacent to said main-casing, one end of said shaft extending through the lower end of said post-member, a driving-shaft journaled in the upper end of said post-member, sprocket-wheels attached respectively upon said transverse shaft and said driving shaft, a driving-chain running over said sprocket-wheels, a detachable hand-crank adapted to be connected with one end of said driving-shaft to apply power thereto, a brake mechanism for locking said power transmission mechanism to hold said refuse-receptacle in elevated position while being dumped.

In testimony that I claim the invention set forth above I have hereunto set my hand this 4th day of October, 1913.

FRANK EHRHARDT.
